UNITED STATES PATENT OFFICE.

JOHN A. WOZENCRAFT, OF CHICAGO, ILLINOIS, ASSIGNOR OF ONE-THIRD
TO JOHN THOMAS MULLINS, OF CHICAGO, ILLINOIS.

GRAPHOPHONE ALARM-CLOCK.

SPECIFICATION forming part of Letters Patent No. 778,434, dated December 27, 1904.

Application filed November 30, 1903. Serial No. 183,266.

To all whom it may concern:

Be it known that I, JOHN A. WOZENCRAFT, a citizen of the United States, residing at Chicago, in the county of Cook and State of Illinois, have invented certain new and useful Improvements in Alarm-Clocks, of which the following, when taken in connection with the drawings accompanying and forming a part hereof, is a full and complete description, sufficient to enable those skilled in the art to which it pertains to understand, make, and use the same.

This invention relates to alarm-clocks wherein there is a time-train and an alarm-train acting independently of each other, but so related that the alarm-train can be set to be released at a determined time, as indicated by the time-train.

The object of this invention is to obtain an alarm-clock in which the alarm-train will be released and actuated relative to the time-train of the clock in the ordinary way and by which the alarm given will consist in words spoken or shouted by a phonograph forming the signal of the alarm-train.

A further object of this invention is to obtain a clock of the kind named wherein the words or sentences spoken or shouted may be repeated several times unless the alarm-train of the clock be stopped.

A further object of the invention is to construct an alarm-clock of the kind named which will occupy but little space in addition to that now required for alarm-clocks of the ordinary kind.

A further object of the invention is to obtain an alarm-clock of the kind named which can be regulated to run at the proper rate of speed to substantially reproduce the tones of the voice of the person making the record.

In the drawings accompanying and forming a part hereof, Figure 1 is a front elevation of a clock embodying this invention. Fig. 2 is a side elevation of a clock embodying this invention. Fig. 3 is a rear elevation of a clock embodying this invention, and Fig. 4 is an elevation of the governor or regulator of the alarm-train of the clock. Fig. 5 is an elevation of the time-train and alarm-train of

the clock removed from the casing. Fig. 6 is a top plan view of the casing of the spring and train actuating the phonograph of the apparatus with a portion of such casing broken away to expose the several parts to view. Fig. 7 is a vertical sectional view of the hollow shaft on which the hub of the cylinder containing the phonographic record is rotatably mounted, such figure showing a section of the back plate of the clock and one end of the center shaft thereof.

A reference letter used to designate a given part is employed to indicate such part throughout the several figures of the drawings wherever the same appears.

A is a clock.

B B are the hands of the clock. An ordinary independent time-train—as, for instance, one comprising spring b on shaft b' , driving-wheel b^2 , center shaft b^3 , on which are mounted the hands of the clock, and wheel b^4 , pinion b^5 , intermeshing with wheel b^6 , such pinion mounted on shaft b^6 , gear-wheel b^7 , also mounted on shaft b^6 , pinion b^8 , intermeshing with wheel b^9 on shaft b^9 , gear-wheel b^{10} on shaft b^9 , pinion b^{11} on shaft b^{12} , such pinion intermeshing with wheel b^{10} , escape-wheel b^{13} on shaft b^{12} , balance-wheel b^{14} , and lever connection b^{15} between the escape-wheel b^{13} and such balance-wheel b^{14} —and alarm-train—as, for instance,

one comprising spring b^{16} and driving-wheel b^{17} on shaft b^{18} , pinion b^{19} on shaft b^{20} , such pinion engaging with the driving-wheel b^{17} , gear-wheel b^{21} on shaft b^{20} , pinion b^{22} on shaft b^{23} , engaging with gear-wheel b^{21} , pinion b^{23} on shaft b^{24} , engaging with gear-wheel b^{21} , gear-wheel b^{25} , also mounted on shaft b^{24} , and pinion b^{26} , mounted on shaft n —are contained in the clock and the ordinary connection between the alarm-train and the time-train of the clock is used. No invention is claimed therefor, and spring or other motors may be used to actuate such trains, respectively, as preferred.

C is a cylinder connected to hub f by arms $F F$, such hub being rotatably mounted on hollow shaft D and such hollow shaft positioned so that the cylinder is concentric to the hour and minute hands of the clock. Shaft D is made hollow, so that the hands of the

clock can be set by a key inserted through the central hole F of such hollow shaft in that class of clocks set by a key from the back.

F F are arms extending from the hub f to the rim forming cylinder C. Hub f turns on hollow shaft D.

Cylinder C when mounted as described is concentric to the dial of the clock, and when round case G is used to inclose the clock, as is illustrated in the drawings, such cylinder is also concentric with such round case.

H is a belt-pulley rigidly mounted on the hub f.

I is a belt-pulley rigidly mounted on rotatable shaft i of the alarm-train of the clock.

J is a belt connecting pulleys H and I and transmitting motion from the pulley I to the pulley H and cylinder C. Hub f and arms F F are positioned with reference to the back plate of the clock, so as to permit the winding-keys K and L to be placed in position, as shown, without interfering with the rotation of the hub and arms.

M M are weights mounted on the spring-arms N N, (see Fig. 4,) respectively, on shaft n. Shaft n is one of the rotatable shafts of the alarm-train of the clock.

O is a disk loosely mounted on shaft n to move longitudinally on such shaft, and one end of each of the respective spring-arms N N is attached to such disk. The opposite ends of such spring-arms are respectively attached to the shaft n, so that as such shaft is rotated by the actuation of the alarm-train of the clock and the weights M M are thereby (by centrifugal force) brought into varying positions relative to the shaft the disk O will be moved longitudinally in a corresponding degree on the shaft n.

P is an adjustable friction-block, against which the disk O is forced by movement of such disk in one direction on shaft n in the manner last above described. Friction-block P is mounted on the arm Q, and R is a thumb-wheel by means of which the arm Q and friction-block P thereon are adjusted relative to the disk O. The desired speed to the cylinder C is thus obtained.

S is an ordinary phonograph-record on cylinder C.

T is a rotatably-mounted post on which the sound-tube T' and horn or trumpet t are mounted, as by the pivot t', to rotate with such post. A spring-actuated train in casing U is connected to the rotatable post T. Casing U may be secured to the clock-casing, as by standard U' and screws u' u'.

u² is the spring of the train in casing U.

u³ is the main driving-wheel of the train.

u⁴ is a pinion on shaft u⁵, intermeshing with the main driving-wheel u³, and u⁶ is a gear-wheel on shaft u⁵, intermeshing with pinion u⁷ on the rotatable post T.

When the spring of the train is wound, as by key u, such spring will turn the post T,

so that the needle S' of the phonographic reproducer S² will follow the marks therefor on the record S and so that when such needle has passed off the record the post T will continue to turn, carrying the reproducer therewith until such needle of the reproducer again enters upon the lines therefor on the record to again repeat the words thereon.

V is a stop rigidly secured to the casing of the phonograph or to the sound-tube of such phonograph, and V' is a corresponding stop rigidly secured to the frame or case of the clock.

W is an incline with which the stop V comes in contact in the rotation of the phonograph and sound-tube thereof around the axis of post T and whereby such stop, together with the phonograph-reproducer and especially the needle thereof, is raised just as such needle again enters onto the record used, and such incline is placed in front of the stop W, so that as the rotation of the reproducer is arrested by stop V coming into contact with the stop V' such reproducer may drop down onto the record, and as it so drops the stop V is carried down to pass out from under the stop V' and the contents of the record be again spoken or shouted through the phonograph.

X is the setting-hand, indicating the time when the alarm-train is intended to be released.

X', Fig. 3, is a pivoted lever to be forced against wheel I and stop the action of the alarm-train of the clock.

When the alarm is desired to be given at a certain time, the time-train and alarm-train of the clock are respectively wound, the hand X is set to the time the alarm is desired to go off, and the needle S' of the reproducer is placed on the record S adjacent to the stop V'. When the alarm-train is released, the cylinder C is turned, together with the record S, and the words on the record are spoken or shouted from the reproducer S² and trumpet t. As the cylinder C rotates when the spring of the train in casing U is wound, such train tends to turn standard T, so moving the needle S' of the reproducer laterally on cylinder C, thus causing such needle to readily follow the marks on record S. As needle S' leaves the record the standard T continues to turn, thereby swinging the reproducer S², sound-tube T', and trumpet t around until stop V rides up incline W and comes into contact with stop V' or drops down off the incline W, (thereby depositing needle S' on record S at the beginning of such record.) The contents of the record are thus repeated, with an interval of silence between such repetitions, until the spring of the alarm-train is run down or until the stop X' is brought against wheel I to stop the train.

Having thus described my invention, its construction, and manner of operation, what I claim as new, and desire to secure by Letters Patent, is—

1. In an alarm-clock, the combination of a phonographic cylinder, a phonographic reproducer, a standard rotatably mounted adjacent to the reproducer, a connection between the standard and the reproducer, an abutment movable with the reproducer, a stationary abutment and an inclined plane in front of the stationary abutment, a time-train, an alarm-train, and a connection between the alarm-train and the phonographic cylinder; substantially as described. 35
2. In an alarm-clock, the combination of a shaft concentric to the dial of the clock, a hub rotatably mounted on the shaft, arms to the hub, a cylinder attached to the arms, an alarm-train, a phonographic reproducer and a connection between the alarm-train and the hub; substantially as described. 40
3. In an alarm-clock the combination of a phonographic cylinder rotatably mounted concentric to the dial of the clock, an alarm-train, a connection between the alarm-train and the cylinder, and a phonographic reproducer; substantially as described. 45
- 25 4. In an alarm-clock, a cylinder provided
- with a record thereon rotatably mounted on the clock-frame, a pulley on the cylinder, a pulley on one of the shafts of the alarm-train, a belt connecting such pulleys, a phonographic reproducer provided with a trumpet, 30 spring-arms on one of the shafts of the alarm-train, a disk attached to the spring-arms and weights on the spring-arms, with an adjustable abutment adjacent to the disk, substantially as described. 50

5. In an alarm-clock, the combination of a cylinder rotatably mounted concentric with the dial of a clock, a pulley on one of the shafts of the alarm-train, a pulley on the cylinder, and a belt connecting such pulleys, a phonographic cylinder, a phonographic reproducer, a trumpet to such reproducer, and a connection between such reproducer and the frame of the clock; substantially as described.

JOHN A. WOZENCRAFT.

In presence of—

CHARLES TURNER BROWN,
JAMES T. CRANE.
